US00D601155S

(12) **United States Design Patent**
Sogabe

(10) **Patent No.:** **US D601,155 S**
(45) **Date of Patent:** **** Sep. 29, 2009**

(54) **PERSONAL DIGITAL ASSISTANT**

(75) Inventor: **Takashi Sogabe**, Tokyo (JP)

(73) Assignee: **Sony Corporation**, Tokyo (JP)

(**) Term: **14 Years**

(21) Appl. No.: **29/290,641**

(22) Filed: **Dec. 28, 2007**

(51) LOC (9) Cl. **32-00**

(52) U.S. Cl. **D14/486; D14/341**

(58) **Field of Classification Search** D14/485, D14/486, 487, 488, 489, 490, 491, 492, 493, D14/494, 495; 455/556.2; 715/215, 227, 715/235, 246, 274, 275, 700, 703, 705, 706, 715/707, 709, 710, 715, 716, 719, 726, 727, 715/728, 730, 739, 752, 753, 756, 758, 759, 715/762, 763, 768, 771, 773, 777, 779, 780, 715/783, 808, 809, 810, 811, 812, 813, 818, 715/819, 820, 821, 822, 823, 824, 825, 828, 715/829, 833, 834, 835, 836, 837, 838, 839, 715/840, 841, 842, 843, 844, 845; 715/846, 715/847, 861, 864, 867, 962, 963, 976, 977, 715/978; 345/902, 952, 953, 955, 956, 960, 345/426, 590, 594, 601, 603, 606, 620, 650, 345/657, 659, 661, 685, 441, 173

(57) **CLAIM**

The ornamental design for a personal digital assistant, as shown and described.

DESCRIPTION

FIG. 1 is a perspective view of a personal digital assistant showing my new design; and,

FIG. 2 is a front elevational view thereof.

The broken line showing of portions of a personal digital assistant is included for purpose of illustrating environmental structure and forms no part of the claimed design. The rectangle shown in broken line forms an unclaimed boundary and the area within forms no part of the claimed design.

1 Claim, 2 Drawing Sheets

FIG. 1

FIG. 2
